UNITED STATES PATENT OFFICE.

ELBRIDGE R. HOLMES, OF WORCESTER MASSACHUSETTS, ASSIGNOR TO CROMPTON & KNOWLES LOOM WORKS, OF WORCESTER, MASSACHUSETTS, A CORPORATION OF MASSACHUSETTS.

STOP FOR WEIGHTS OF MULTIPLE-NEEDLE DETECTORS.

Application filed December 21, 1925. Serial No. 76,822.

This invention relates to multiple needle and preventing the aforesaid undesirable results.
weft detectors for looms of the type employing an individual weight for each needle detector and it is the general object of the invention to provide an improved stop to limit the motion of the weights to prevent undesirable motion thereof.

In Patent No. 1,583,135, there is shown a detector of the multiple needle type wherein each detector needle has associated therewith a freely movable weight the purpose of which is to exert a light pressure on the needle so that the same will penetrate a very thin layer of yarn, thus rendering unnecessary the winding of a bunch on the bobbin. Detectors of this type when applied to the usual style of automatic box loom are so located that the weights swing upwardly and strike the hub of the transfer lever and it is found that due to this action the weights are deformed to such an extent that they do not work with proper freedom. It is an important object of my invention to provide a stop for the weights which shall be yieldable to the end that said weights will not be deformed and in carrying out this feature of my invention I employ the arm already provided on detectors of this type for withdrawing the detector needles on the transferring beat of the loom.

If the loom is running at a relatively high rate of speed it is found that the blow of the yarn against the rear ends of the detector needles swings the weights away from the needles and as the weights rebound they strike the needles a blow which tends to push said needles through the yarn and into one of the holes formed in the wooden portion of the barrel. The needles are formed of wires which have two parallel arms the upper of which cooperates with a so-called actuator lever having a downward motion when the lay is substantially in its extreme forward position and if the blow struck the needles by the weights comes too late to penetrate the yarn then the upper arm of the needles will be driven against the actuator lever to score the latter and in time it is found that the lever and the needles do not cooperate as they should. It is a further object of my invention to place the stop for the weights in such position that excess movement of the weights is prevented, thus avoiding the blow given the needles

It is a further and more particular object of my invention to place the stop for the weights on the carrier which supports said weights and wires to the end that said stop will be in proper relation with respect to the weights in all adjusted positions of the detector.

With these and other objects in view which will appear as the description proceeds, my invention resides in the combination and arrangement of parts hereinafter described and set forth in the claims.

In the accompanying drawings wherein I have shown a convenient embodiment of my invention,

Fig. 1 is a side elevation of a detector embodying my invention, certain parts being shown in section,

Fig. 2 is a top plan view taken in the direction of arrow 2, Fig. 1, and

Fig. 3 is a perspective view of the mounting for the stop.

Referring to the drawings it will be seen that I have provided a stand 10 secured in any approved manner to fixed structure such as a loom side and I provide said stand with slots one of which is indicated at 11 in Fig. 1. A support 12 is held to the stand by means of bolts 13 one of which is indicated in Fig. 1 and the slots 11 permit vertical adjustment of the support with respect to the stand. A needle carrier 14 is provided with a notch 15 which receives a tongue or rib 16 extending horizontally on the upper end of the support 12. A bracket 17 formed preferably of sheet metal is secured by means of screws 18 to the forward lower face of the carrier 14 and has upper and lower arms 19 and 20, respectively. The lower arm of the bracket has secured thereto the forward end of a tension spring 21 the rear end of which extends through the lower end of carrier 14 and the upper end of support 12 and is held in position by means of a pin 22 held against the rear face of the support 12 by the tension of the spring. In this way the carrier may move angularly with respect to the support 12 and may also move forwardly should a bobbin be caught between the rear end of the carrier and the advancing lay.

Mounted for free sliding motion in said

carrier is a plurality of needles 23 each having a lower yarn engaging arm 24 and an upper indicating end 25 positioned for co-operation with an actuator lever 26. Said needles cooperate with the bobbin W the barrel of which is provided with a plurality of spirally arranged openings as set forth in Patent No. 1,220,685. When a sufficient supply of weft is present all the needles will be moved forwardly so that actuator lever 26 may move downwardly but when insufficient weft for continued weaving is present one or another of the needles will enter an opening in the bobbin and the indicating arm 25 corresponding thereto will arrest downward motion of the actuator lever to give an indication of weft exhaustion.

Said carrier 14 supports a stud 27 on which is mounted for free pivotal motion a withdrawing arm 28 illustrated in Fig. 3, said arm 28 having spaced bearing through which the stud 27 passes and on which said arm pivots, and hanging as shown in full lines in Fig. 1 by gravity. A withdrawing finger 29 extends behind the upright portions 30 of the needles and operates to withdraw the needles 23 out of the path of the indicating bobbin at the time of transfer, this motion being accomplished by engagement of some part of the transerrer arm (not shown) with the laterally extending wing 31. Excess forward movement of the needles is prevented by the upbent end 32 of the upper arm 19 of the steel bracket 17. Also mounted on said stud 27 is a plurality of weights 33 each having a rearwardly extending portion 34 to engage the upright part of a needle to hold it yieldingly in rearward position. The matter thus far described is substantially the same as the structure set forth in the aforesaid co-pending application and also in Patent No. 1,549,960.

As previously stated it is found that as the weft advances with the lay it engages the needles and the weights 33 are found to have an undesirable motion about the pivot 27 resulting in deforming said weights and also rebounding of the same to cause improper action of the needles either on the weft supply or on the forward face of the actuator lever 26. In carrying out my improvements I form the withdrawing arm 28 with a pair of forwardly extending arms 40 between which extends a stop rod 41 freely rotatable in the arms and preferably though not necessarily formed of a slightly resilient material such as rawhide. Said stop rod 41 is so placed that when a full bobbin is in extreme forward position the weights 33 when in engagement with the needle detectors will be immediately below the rod 41. Should said weights tend to move beyond their proper position they will engage the rod 41 and lift the withdrawing arm 28 from the full line position to the dot and

dash line position indicated in Fig. 1 against gravity. In this way the weights are restrained in a manner which will not deform them and the weights are also held against movement to an elevated position from which they could fall and strike the needles to give the latter the undesirable movements previously described. Obviously, any vertical or horizontal adjustment of the detector can be made without disturbing the proper position of the stop rod 41 with respect to the weights.

From the foregoing it will be seen that I have provided a yieldable stop for the weights of multiple needle weft detectors, said stop being capable of slight motion to prevent deforming of the weights and also being so located as to resist excess movement to prevent rebounding of said weights and being mounted on the usual withdrawing arm of such detectors. It will also be seen that the stop moves with the detector when the latter is adjusted so as to preserve the proper relation between said stop and the weights.

Having thus described my invention it will be apparent that changes and modifications may be made therein by those skilled in the art without departing from the spirit and scope of the invention, and I do not wish to be limited to the details herein disclosed but what I claim is:

1. In a weft detector having a plurality of yarn engaging detector needles and weights for said needles to hold said needles yieldingly against the yarn, a stop yieldingly mounted and positioned to engage the weights to restrain excess movement thereof. 100

2. In a weft detector having a plurality of yarn engaging detector needles and weights for said needles to hold said needles yieldingly against the yarn, in combination, a pivotally mounted arm movable against gravity to withdraw the detector needles, and a stop mounted on said arm and movable therewith against the action of gravity when engaged by the weights to restrict excess movement of the latter. 110

3. In a weft detector having a plurality of yarn engaging detector needles and weights for said needles to hold said needles yieldingly against the yarn, in combination, a carrier for the detector needles, an arm yieldingly mounted on the carrier, and a stop mounted on and movable with the arm to engage and yieldingly resist excess movement of the weights. 115

4. In a weft detector having a plurality of yarn engaging detector needles and weights for said needles to hold said needles yieldingly against the yarn, means to prevent excess movement of said weights beyond the position corresponding to the position occupied by the needles when the latter are in their foremost position. 125

5. In a weft detector for looms, a stand, a plurality of needle detectors adjustably supported with respect to the stand, a plurality of weights one for each needle detector moving with the needles when the latter are adjusted with respect to the stand, and a stop for the weights to restrict excess movement thereof, said stop also being movable with the needles and the weights when 10 said needles and weights are adjusted as to position with respect to the stand.
6. In a weft detector for looms, a stand, a support adjustably mounted on the stand, a plurality of needle detectors, a carrier for 15 said detectors adjustably mounted on the support, a plurality of weights one for each needle detector mounted for free pivotal motion with respect to the carrier, and a stop supported by the needle carrier and positioned to prevent excess movement of 20 said weights beyond the position corresponding to the foremost position of the needles when the latter are moved forwardly by engagement with the supply of yarn.
7. A detector withdrawing and weight restraining member for a weft detector having a plurality of needle detectors and a weight for each detector movable freely about a pivot, said member having bearing portions for the pivot of the weights, and having 25 portions to engage the detectors to withdraw the same, and said member also being provided with a stop to restrain excess movement of the weights.
- In testimony whereof I have hereunto 30 affixed my signature.

ELBRIDGE R. HOLMES.
